Primary Examiner — Nicole C Shiflet*Assistant Examiner* — Danielle Nichole Bowly(74) *Attorney, Agent, or Firm* — Rosenberg, Klein & Lee(57) **CLAIM**

The ornamental design for an organizer with magnetic elements, as shown and described.

DESCRIPTION

FIG. 1 is a perspective view of an organizer with magnetic elements showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view in use.

The broken lines showing in FIG. 8 depict environment and form no part of the claimed design.

1 Claim, 8 Drawing Sheets(56)
